ARMED TURRET

Ernest E. Chase, Ernest S. Nokes, and Frank E. Stratton, Beverly, and William V. Goodhue, Ipswich, Mass., assignors to United Shoe Machinery Corporation, Flemington, N. J., a corporation of New Jersey

Application March 27, 1945, Serial No. 585,150

8 Claims. (Cl. 89—41)

1
This invention relates to ordnance and is illustrated as embodied in an armed turret which may be advantageously used, for example, at the entrances of rivers and harbors for protection against low-flying airplanes and small boats.

It is desirable to concentrate guns of relatively small caliber around coastal defenses in order to ward off attacks by enemy aircraft. Such guns should be effective for the purposes intended and should be of suitable construction to insure their being readily set up at vantage points in the menaced areas.

It is an object of the present invention to provide an armed turret which may be readily set up wherever desired and which may be quickly and effectively trained on fast-moving targets.

The illustrative armed turret, which comprises a single gun of the Bofors 40 mm. type, is operated by a crew comprising a commander, azimuth and elevation trackers, and a gunner, mechanism being provided by which the commander may initially pick up, and train the gun on, the target and then turn control of the turret over to the trackers. Thereafter, the trackers, by the use of combined manual and power-operated rate control mechanism, rotate the turret, together with the gun, in azimuth and the gun in elevation while observing the target through their respective sights, the deflection angles between the gun and the trackers' and the observer's sights during such time being varied by lead setting mechanism controlled by the commander in accordance with the observed effect of fire upon the target.

The various features of the invention will be understood and appreciated from the following detailed description read in connection with the accompanying drawings, in which

Fig. 1 is a perspective outside view of an armed turret in which the present invention is embodied;

Fig. 2 is another perspective outside view of the turret, a portion of the interior of which is shown through an open door at the rear of the turret;

Fig. 3 is a plan view of a unit of an ammunition rack, which is mounted on an inside wall of the turret, supporting a clip of cartridges;

Fig. 4 is a rear end view of three of the units of the ammunition rack, a gunner being in the act of withdrawing a clip of cartridges from the center of said units;

2
Fig. 5 is a side view, partly in longitudinal vertical section, of the interior of the turret;

Fig. 6 is an enlarged side view, partly broken away, showing in detail portions of the mechanism illustrated in Fig. 5;

Fig. 7 is a rear view, partly broken away, of the turret as viewed on line VII—VII of Fig. 5;

Fig. 8 is a view on line VIII—VIII of Fig. 5;

Figs. 9 and 10 are detail views, showing portions of firing mechanism;

Figs. 11 and 12 are enlarged sectional and perspective views, respectively, showing a cover of a cupola of the turret;

Fig. 13 is a view, partly in side elevation and partly in section, showing an open sight mounted upon the cupola and mechanism through which the sight is operated;

Figs. 14 and 15 are plan and rear views, respectively, partly in section, of mechanism through which a commander of the turret operates control box levers which regulate the speed of azimuth and elevation electric drive motors, respectively;

Fig. 16 is a section on line XVI—XVI of Fig. 14;

Fig. 17 is a section on lines XVII—XVII of Fig. 15, showing the interior construction of azimuth and elevation solenoids controlled by the commander;

Fig. 18 is a section on line XVIII—XVIII of Fig.

19, showing details of a dashpot construction;

Figs. 19 and 20 are sections on lines XIX—XIX, XX—XX, respectively, of Fig. 18;

Figs. 21 and 22 are side and front views, respectively, partly in section, showing mechanism operated by the azimuth tracker for rotating the turret and also showing portions of electric drive mechanism which is controlled by the tracker and aids said tracker in the rotation of the turret;

Fig. 23 is a skeleton view of operating portions of the mechanism illustrated in Figs. 21 and 22;

Fig. 24 is a perspective view of a sight used by the azimuth tracker;

Fig. 24A is a section on line XXIV—XXIV of Fig. 24;

Fig. 25 shows the sight, partly in side elevation and partly in section on line XXV—XXV of Fig. 24;

Fig. 26 is a section on line XXVI—XXVI of Fig. 25;

Fig. 27 is a view showing, partly in section and

partly in side elevation with covers removed, portions of the commander's sight and a lead setting box by the use of which the commander "throws" leads into the various sights;

Fig. 28 is a section on line XXVIII—XXVIII of Fig. 27;

Fig. 29 is a plan view of the lead setting box;

Fig. 30 is a diagrammatic view, showing the various connections between the gun, the lead setting box, and the sights;

Fig. 31 is a wiring diagram; and

Fig. 32 is a diagram used in connection with the description of azimuth and elevation lead setting mechanism.

The illustrative armed turret 38 comprises a Bofors 40 mm. gun 40 such as described in Ordnance Pamphlet No. TM9-252, rate controlled electrically operated means for rotating the turret, together with the gun, in azimuth and the gun in elevation with relation to the turret, and manually operated mechanism for actuating said means, portions of said mechanism being operated by a turret commander for initially training the gun on a target. After the gun 40 has been trained on the target, the commander renders his rate control actuating mechanism inoperative, the training of the gun thereafter being turned over to azimuth and elevation trackers who are seated on stools 42, 44 (Fig. 5), respectively, and drive the turret, through mechanical connections hereinafter described, said connections at such time being adapted to actuate said rate controlled electrically operated means, which may be referred to as aided tracking means and assists the trackers in following the target.

The commander, standing upon a platform 46 (Figs. 5, 8 and 9) and observing or "spotting" the target through an open sight 48 (Figs. 1, 2, 5, 13 and 30) mounted upon a cupola 50 of the turret 38, initially trains the gun 40 on the target by the use of a grip 52 (Figs. 5, 14 and 16) forming part of hereinafter-described rate control mechanism, a hatch cover 54 (Figs. 1, 2, 5, 11 and 12) of the cupola being open in the dash line position shown in Fig. 11. The commander then moves to a seated position upon a stool 56 (Figs. 5 and 8), which is positioned above the platform 46, and shuts the hatch cover 54, the target thereafter being observed by him through an elbow telescope 58 (Figs. 1, 2, 5 and 30) as he trains the gun 40 on the target. While the gun 40 is being initially trained on the target, the azimuth and elevation trackers observe said target through elbow telescopes 60, 62 (Figs. 1, 5 and 30), respectively, extending outside the turret 38 and forming parts of sights hereinafter described.

When the commander has trained the gun 40 on the target he releases solenoid control buttons 64 (Fig. 14) located on the grip 52, thereby transferring control of the electrically operated means to the azimuth and elevation trackers who turn wheels 66 (Figs. 5, 21, 22 and 23) 68 (Fig. 5), respectively, to retain, through mechanism which will appear later, horizontal and vertical hair-lines (not shown) of the elbow telescopes 60, 62, respectively, and accordingly the gun 40, on the target. The commander now being free to observe the fire on the target, throws leads into the elbow telescopes 58, 60 and 62 by turning azimuth and elevation wheels 70, 72 (Figs. 5, 28, 29 and 30) of a lead setting box 74 in accordance with the observed trajectory of tracer bullets fired at the target, thereby causing the trackers to shift the fire to the target, if necessary, and thereafter

to maintain said fire upon the target as it changes its speed and/or direction.

A floor 76 (Figs. 5, 6, 7, 21 and 22) of the turret 38 is provided with a depending annular flange 78 (Fig. 5) the inner face of which is in engagement with a cylindrical surface of an upstanding ring bracket 80 secured by screws 82 to a fixed base 84 (Figs. 1, 2 and 5). Secured by screws (not shown) to the base 84 are eight uniformly spaced bearing blocks 86 (Fig. 5) carrying rollers 88 engaged by a bottom plate 90 of the floor 76 of the turret. In order to insure against dirt being blown into the bearing blocks 86, there is provided a circular plate 92 which is secured to the base 84 and the upper end of which is slightly spaced from the bottom plate 90, said space being sealed by an annular felt piece 94. Secured by screws 96 to the bracket 80 is a ring gear 98 (Figs. 5, 21 and 22) having teeth which are arranged in meshing relation with teeth of a gear 100 (Figs. 21 and 22) mounted upon a shaft 101 rotatably mounted in bearings 102 of a housing 104 secured by screws 106 to the floor 76 of the turret. Rotation of the gear 100, by mechanism which will be described later, causes the turret to rotate about an axis 108 (Fig. 5) of the ring gear 98.

Electric current is supplied to the turret through a collector ring unit 110 (Figs. 5 and 30) which is bolted to the upstanding ring bracket 80 and comprises two large rings 112 (Fig. 5) for supplying power and four small rings 114 for supplying current through suitable wiring connections to light fixtures and to solenoids, as will appear later. Two heavy and four light power take-off brushes 116 (Fig. 31) on a brush holder (not shown) secured to the turret floor 76 engage the outer races, respectively, of the collector rings and transmit current to a switch box 118 (Figs. 5 and 31). Surrounding the rings 112, 114 and the brushes 116 is a collector ring guard 120 secured to the turret floor 76.

The upstanding walls of the illustrative turret are welded or otherwise secured to the floor 76 and to the top of the turret as well as to each other, the front wall and the top of the turret for protection being approximately one inch thick and the other walls of the turret being approximately one-half inch thick. There is provided in the front wall of the turret 38 an arcuate opening 122 (Fig. 1) sufficiently large to permit elevation of the gun through ranges varying from minus 15 to 90° from the horizontal and a small opening 124 (Figs. 1, 5 and 6) in the lower front portion of the turret for the reception of a chute 126 (Figs. 1, 2, 5, 6 and 7) for disposing of empty cartridge cases. There are also provided at the right side of the turret 38 three openings 128 (Figs. 1, 2 and 25) for receiving sights 130 (Figs. 1, 2, 24, 25, 27 and 30) formed in part by one of the elbow telescopes 58, 60, 62.

A pair of trunnions 132 (Figs. 5, 6, 7 and 30) secured to a breech casing 134 of the gun 40 are mounted for rotation in horizontal bores of trunnion blocks 136 bolted to trunnion block supports 138, 140 (Fig. 7) which are bolted or otherwise rigidly secured to the floor 76 of the turret and are connected together by a transverse cylindrical web 142. Accordingly, the gun rotates with the turret for training in azimuth and is rotated, through mechanism hereinafter described, about the common axis 144 of the trunnions 132 with relation to the turret for training the gun in elevation. In order to swing the gun in elevation, there is secured to the breech casing 75 134 of the gun a segment gear 146 driven by a

gear 148 which is rotatable, through mechanism described later, in response to movement of the rate control mechanism actuated by the commander's grip 52 or in response to movement of the elevation tracker's wheels 68 and the rate control mechanism actuated by said wheels.

In order to insure that the arcuate opening 122 (Fig. 1) in the front wall of the turret 38 shall be closed as the gun 40 is moved into different elevated positions, there is secured to the breech casing 134 of the gun, through a bracket 150 (Fig. 5, 6 and 7) and a pair of brackets 152, an arcuate shield 154 which is of U-shaped cross section, as shown in Fig. 7, and fits slidably between arcuate flanges 156 (Figs. 5 and 6) extending inward from the front walls of the turret. A curved trough 158 (Figs. 5 and 7) secured to the rear end of the breech casing 134 of the gun 40 deflects cartridge cases ejected from the gun into the chute 126, a lower portion of which is secured by bolts 160 to a standard 162 bolted to the turret floor 76 and the front end of which extends through the opening 124 in the front wall of the turret and is secured to said wall by a bracket 164 (Figs. 1, 5 and 6). An upstanding portion of the chute 126 is formed integral with a bracket 166 mounted upon a fulcrum pin 168 secured to the standard 162. As the gun is elevated the upstanding portion of the chute 126 is engaged by the arcuate shield 154, causing said upstanding chute portion to pivot counterclockwise, as viewed in Fig. 5, about the axis of the fulcrum pin 168 against the action of a spring 170 (Fig. 6) which is mounted upon a bolt 172 (Figs. 2, 6 and 7) the upper end of which is threaded into a fulcrum pin 174 swiveled upon the bracket 166. The bolt 172 passes through an enlarged opening in a flange of the standard 162, opposite ends of the spring 170 engaging a washer supported by a face of said flange and the head of the bolt, respectively.

In order that the gun 40 may be balanced as nearly as practicable for movement about the axis 144 of the trunnions 132, there are provided at opposite sides of the chute 126 equilibrators 176 (Figs. 2, 5, 6 and 7). As best shown in Fig. 6, each of the equilibrators comprises a plurality of springs 178 which are encased in a housing 180 and are compressed upon forward movement of a plunger rod 182 (Figs. 6 and 7). Each of the plunger rods 182 is slidably supported in an elongated bore of a header 184 (Fig. 6) which is secured by bolts 186 to a bracket 187 welded to the trunnion block supports 138, 140. The housings 180 for the springs 178 are welded or otherwise secured to their associated headers 184 and are secured by screws 188 (Fig. 7) to the standard 162. Secured to the forward end of each of the plunger rods 182 is a chain 190 which passes over pulleys 194, 196 supported rotatably by an associated trunnion block support 138, 140 and which has its upper end coupled to a rod 192 secured to the segment gear 146.

Ammunition racks

Mounted upon the left inner side wall of the turret 38 as shown in Fig. 2, are vertically arranged ammunition racks 198 each comprising a bracket 200 (Figs. 2, 3 and 4) which is L-shaped in cross section and is fulcrumed upon a pin 202 (Figs. 3 and 4) secured to an angle bar 204 welded to the turret wall. Each of the brackets 200 is adapted to swing upward upon its associated fulcrum pin 202 and is of suitable size to support a clip 206 containing four cartridges, the forward ends of the cartridges in the clip being

supported by a bar 208 of the rack mounted upon a fulcrum pin 210 carried by an angle bar 212. Each of the brackets 200 and its associated bar 208 may be referred to as a rack unit. The cartridges in the clips 206 are placed in front and rear cartridge guides 214, 216 (Figs. 5, 6, 7 and 30), respectively, of the gun 40 by the gunner, who usually empties the vertically arranged racks progressively from the top.

10 The brackets 200 and the bars 208 are normally arranged at an angle of approximately 15° to the turret side wall, the wall-abutting faces 218, 220 (Fig. 4) of the brackets and the bars, respectively, at such time being in engagement with said wall, the arrangement being such that the brackets and the bars of the empty racks may be swung upward when ammunition is removed from the lower racks. By mounting the brackets 200 and the bars 208 of the racks 198 for pivotal movement as above described, the gunner may drag the loaded clips 206 out of the racks at the most advantageous angle considering the stature of the gunner and the position of the particular rack from which the clip is being removed. With the above construction, more clips may be stored in a given space than in a construction in which the brackets and bars are rigidly fixed to the turret.

Commander's platform

30 The commander's platform 46 (Figs. 5 and 8) is secured to a pair of rods 222 the lower ends of which pass through vertical bores formed in lugs 224 secured to said rear wall of the turret, the upper ends of said rods registering in vertical bores of lugs 226 which are also secured to said rear wall of the turret. Arranged in notches 228 (Fig. 5) of the lugs 224 and threaded onto the rods 222 are nuts 230 which may be rotated to raise and lower the rods, together with the platform 46. In order to raise or lower the platform 46, the nuts 230 are provided with spiral teeth 232 constructed and arranged to mesh with teeth of spiral gears 234 (Fig. 8) which are secured to shafting 236 rotatably mounted in the lugs 224 and are conveniently rotated by a hand crank 238. The commander's stool 56 is threaded into a bracket 244 pivotally supported upon one of the rods 222, a ladder 242 being provided to assist the commander in climbing onto the platform 46.

Firing mechanism

55 The gun 40 is fired by the commander by depressing a treadle 244 (Figs. 5, 8 and 9) which extends through a slot 246 (Fig. 8) in the platform 46 and is secured at its lower portion to one end of a shaft 248 (Figs. 8 and 9) journaled in a depending boss 250 of the platform. Pinned to the other end of the shaft 248 is a bifurcated lever 252 connected through a universal coupling 254 to an offset bell-crank lever 256 comprising a shaft 258 journaled in a boss 260 of the platform. Pinned to the lever 256 is a clevis 262 to 60 which is secured a rod 263 attached to a flexible cable 264 (Figs. 7 and 8) surrounded by a spiral casing 266. The casing 266 extends through and is clamped to a guide 268 (Fig. 8) which is secured to a bracket 270 bolted to the web 26 of the platform. The cable 264 and its casing 266 extend forward and to the left into a guide 272 (Fig. 7) which is mounted upon the trunnion block support 140 and to which the casing is secured. The forward end of the cable 70 264 is secured to a rod 273 connected through a

coupling 274 to the right end of a rod 276 (Figs. 6, 7 and 10) passing through a recess 278 of the trunnion block support 138 and pivotally connected to the lower end of a bell-crank lever 280 journaled upon a fulcrum pin 282 (Figs. 6 and 10) carried by said support, the upper end of the bell-crank lever being pivotally connected to a housing 284. Extending through a bore in the upper end of the housing 284 is a rod 286 and surrounding the rod and interposed between a head of the rod and the upper end of the housing is an overload spring 288 which normally causes a stop nut 290 on the rod to be forced against the upper end of the housing.

The rod 286 is coupled to a rod 292 (Figs. 5, 6, 7 and 10) pivoted to one arm of a bell-crank lever 294 which is fulcrumed upon a pin 296 mounted upon a bracket 298 bolted to the trunnion block support 138 and which is provided with an elongated slot 300 (Fig. 10) for receiving a pin 302 (Figs. 6 and 10) carried by a lever 304 pivotally mounted upon a shaft 306 fixed to the bracket. Arranged opposite the upper end of the lever 304 and extending into a bore 308 (Fig. 10) of the left trunnion 132 is a firing plunger 310 (Figs. 7 and 10) which may be forced into the bore of said trunnion to actuate firing mechanism (not shown) of the gun. When the plunger 310 is held depressed in the bore 308 by the lever 304 and the gun is set for automatic fire, the gun fires continuously. The lever 304 is normally in its idle position, shown in Figs. 7 and 10, the lever being held in said position by a spring 312 (Fig. 10) one end of which is attached to the bell-crank lever 280 and the other end of which is secured to a stud 314 carried by the trunnion block support 138. By operating the trigger mechanism through the overload spring 288, the plunger 310 cannot be forced with excessive pressure against the firing mechanism (not shown) of the gun. When the commander removes his foot from the treadle 244, the above-described mechanism for firing the gun is moved to its illustrated idle position by the spring 312 and the overload spring 288.

Open sight

The open sight 48, which is used by the commander in initially training the gun 40 on the target, is mounted upon an L-shaped arm 316 (Figs. 1, 5, 13 and 30) pinned to a shaft 318 mounted in a housing 320 (Figs. 5 and 13) extending from the left sloping side 322 (Fig. 13) of the cupola 50. Formed integral with the arm 316 is a counterweight 324 (Figs. 5 and 13) for balancing the arm and the sight about the axis of the shaft 318. The axis or line of vision 326 through the sight 48 is at all times parallel to the axis 328 (Fig. 5) of a tube or barrel 330 (Figs. 1, 5 and 30) of the gun 40, the arm 316 being rocked about the axis of its shaft 318 to the same degree that the tube 330 is moved in elevation about the axis 144 (Fig. 7) of its trunnions 132. In order to rotate the shaft 318 in response to movement of the tube 330, there is secured to the shaft a spiral gear 332 (Figs. 13 and 30) meshing with a spiral gear 334 secured to the forward end of an arm 336 rotatably mounted in bearings of the housing 320 and having secured to it a bevel gear 338 meshing with a bevel gear 340 secured to the upper end of a vertical shaft 342 rotatably mounted in a bearing of the housing and movable, through connections which will be hereinafter described, in

response to movement of the gear 148 (Figs. 6 and 30).

Cupola cover

The hatch cover 54 (Figs. 1, 2, 5, 11 and 12) of the cupola 50 may be quickly and effectively closed by the commander with a minimum amount of effort after the target has been brought into the commander's open sight 48. The cover 54 rests upon rolls 344 (Fig. 11) rotatably mounted upon brackets 346 secured to the cupola and is guided by U-shaped lugs or guides 348 (Figs. 1, 2 and 11) secured to the outer face of the cupola. A pair of rolls 350 supported upon outriggers 352 secured to the rear end of the cupola serve as supports for the cover 54 when it is slid rearward to its open position, shown in full and dash lines in Figs. 1 and 11, respectively.

Secured to the forward end of the inside face of the cover 54 is a plate 354 (Figs. 11 and 12) to a boss of which is pivoted a hook-shaped latch 356 (Figs. 5, 11 and 12) constantly urged clockwise, as viewed in Fig. 11, by a spring 358. When the cover 54 is open, movement of the latch 356 acted on by the spring 358 is limited by the engagement of said latch with the plate 354. When the cover 54 is in its closed position, shown in Figs. 11 and 12, the latch 356 is in engagement with an undercut face of a hook-shaped bar 360 secured to the cupola. Mounted upon a fulcrum pin 362 carried by a boss of the plate 354 is a handle 364 connected through a link 366 to the latch 356, counterclockwise movement of the handle, as viewed in Fig. 11, being effective to disengage 35 the latch from the undercut face of the hook-shaped bar 360 to permit the cover to be moved to its open position.

A forward portion 368 of the cover 54 is hinged to a rear slidable portion 370 of the cover by a fulcrum pin 372 passing through aligned bores in hinges 374 which are secured to said cover portions and have abutments 376 which are in engagement with each other when the cover is in its open dash-line position, shown in Fig. 11, the 45 rear portion of the cover having secured to it undercut lugs 378 which, when the cover is closed, are drawn tightly against bars 380 of the turret 38.

In opening the cover 54, the commander grasps 50 the handle 364 and, after swinging said handle rearward to disengage the latch 356 from the hook-shaped bar 360, simultaneously swings the forward portion 368 of the cover upward and slides the rear portion 370, together with the forward portion 368 of the cover, rearward to its open position.

Commander's rate control mechanism

The mechanism by the use of which the commander actuates the above-mentioned electrically operated means to cause the turret 38 to be rotated and the gun 40 to be moved in elevation will now be described in detail. The electrically operated means, which may be referred to as the 60 electric drive, comprises azimuth and elevation motors 382 (Figs. 5, 21, 22, 23 and 31), 385 (Figs. 5 and 31), respectively, an electric rate control unit including a control box 386 (Figs. 5, 14, 15 and 31), and a resistor unit 388 (Figs. 5 and 31) 65 which is arranged beneath the commander's platform 46 and absorbs surplus energy of the motors. Transmission of power from the switch box 118 to the electric drive is controlled by a power box 390, provided with a switch 392, and also by 70 a stop-and-start switch 394 which is arranged, as 75

shown in Fig. 5, directly above the power box and is turned on prior to turning on the power box switch. The electric rate control unit is adapted accurately to control the speed of the azimuth and elevation motors 382, 384 through ranges varying from zero to 6000 revolutions per minute through an electrical governor system which is sensitive within very close limits for carrying from zero to full load torque, it being possible to vary the speed by infinitely small increments. Since the electric drive forms no part of the present invention, it is not described herein in detail. It will be understood, however, that if desirable, any one of numerous commercial electric or hydraulic drives having rate control units actuated by levers, for example, may be substituted for the illustrative electric drive.

The mechanism for actuating the control box 386 of the electric rate control unit comprises the above-mentioned grip 52, which is operatively connected, by mechanism which will now be described, to azimuth and elevation levers 396, 398 (Figs. 14 and 15), respectively, of said box. The grip 52 is pinned to a shaft 400 (Figs. 14 and 16) fitting in alined bores 402 (Fig. 14) of a bracket 404 (Figs. 14 and 16) which has a depending cylindrical portion rotatably mounted in a cylindrical bearing boss 406 of a frame 408 rigidly secured to the turret wall. Secured by a clamp screw 410 (Fig. 14) to the lower end of the cylindrical portion of the bracket 404 is a sleeve 412 (Fig. 16) having formed integral with it a lever 414 (Figs. 14 and 16) to which is pivoted a rod 416 operatively connected, through mechanism hereinafter described, to the azimuth lever 396 of the control box 386. Rotation of the grip 52 about the vertical axis 418 of the cylindrical boss 406 to operate the azimuth lever 396 is limited in opposite directions by the engagement of forwardly projecting lugs 420 of the bracket 404 with a stud 422 secured to the fixed frame 408. Displacement of the lever 396 in opposite directions from a neutral position by the commander determines the rate of rotation of the turret 38 in opposite directions, respectively.

Secured by a clamp screw 424 to the shaft 400 which is pinned to the grip 52 is a lever 426 pivoted at its forward end to a vertical rod 428 (Fig. 16) which passes down through a bore of the cylindrical boss of the bracket 404 and is pivotally connected at its lower end to a bell-crank lever 430 fulcrumed on a pin 432 carried by the fixed frame 408. The upper end of the bell-crank lever 430 is pivotally connected to a horizontal rod 434 (Figs. 14 and 16) operatively connected, through mechanism to be described, to the control box lever 398, displacement of which by the commander in opposite directions from a neutral position determines the rate of rotary movement of the gun 40 in opposite directions, respectively, about the axis 144 (Fig. 7) of its trunnions 132. The lever 426 has formed integral with it a pair of lugs 436 (Fig. 16) which, when brought into engagement with a pin 438 on the bracket 404, limit movement of the grip 52 about the axis 440 of the shaft 400 and therefore limit the rate of swinging movement of the gun 40 about the axis 144 of its trunnions 132.

The rod 416 enters a cylindrical overload coupling housing 442 (Figs. 5, 14 and 15) and has a head 444 (Fig. 14) between which and the rear end of the housing is interposed a spring 446. Extending through an opening in the forward end of the housing 442 is a rod 448 (Figs. 14 and 15) provided with a head 450 (Fig. 14), a spring

428 being interposed between said head and central wall of the housing. The housing 44 and its associated mechanism may be referred to as an overload coupling and, together with dashpot 454 (Figs. 14, 15, 18, 19 and 20) herein after described, provides insurance against sudden or overcontrolling movement of the azimuth lever 396 of the control box 386.

The rod 448 is pivotally connected through a lever 450 (Figs. 14 and 15) to the upper end of a vertical shaft 458 which is mounted rotatably in bosses 460 (Fig. 15) of the fixed frame 408 and has secured to its lower end a lever 462 pivotally connected through a rod 464 to the azimuth lever 396 of the rate control box 386. Pinned to the central portion of the vertical shaft 458 is a segment gear 466 which has small 30° pressure angle teeth 468 and which, when the solenoid energizing buttons 64 of the commander's grip 52 are released, are engaged by correspondingly shaped teeth 470 of a gear 472 secured to a split collar 474 pinned to the upper end of an upstanding shaft 476. As will appear later, the gear 472, which is rotated by the azimuth tracker, is not in driving relation with the segment gear 466 when the buttons 64 on the grip 52 are depressed. Also fixed to the shaft 458 is a lever 478 secured by a link 480 to a lever 482 of the dashpot 454, the construction of which will be described later.

The hand grip 52 is constantly urged to a neutral position in which the lugs 420 of the bracket 404 are held equally spaced from the fixed stud 422 and in which the segment gear 466 is in the position shown in Fig. 14, by a pair of centralizing arms 484 which, when the grip is released, are moved into engagement with fixed stops 486 on the frame 408 by a spring 488, said arms 484 bearing against a block 490 secured to the rod 464.

Pivoted to the elevation lever 398 of the control box 386 is a rod 492 which is operatively connected to the rod 434 through an overload coupling 494 (Figs. 5 and 14) identical with the above-described overload coupling which connects the shafts 416 and 448 and through which

45 the azimuth lever 396 is operated.

In order that the elevation lever 398 may be controlled by the elevation tracker after the commander has released the solenoid energizing buttons 64, a control box shaft 496 to which the elevation lever 398 is secured is operatively connected through a shaft 497 to a shaft 498 (Fig. 15) rotatably mounted in bearings of the fixed frame 408 and having secured to it a bevel gear 500 which meshes with a bevel gear 502 fixed to a vertical shaft 504 also rotatably mounted in bearings of the fixed frame 408. Pinned to the upper end of the shaft 504 is a segment gear 506 and pinned to the lower end of the shaft is a lever 508 connected through a link 510 (Fig. 14) to a lever 512 (Figs. 14 and 15) of the dashpot 454. Meshing with small 30° angle teeth 514 of the segment gear 506 is a gear 516 which has teeth 518 similar to the teeth 514 of the segment gear and which is secured to a split collar 519 (Fig. 15) pinned to the upper end of an upstanding shaft 520.

As will be explained later, the upstanding shafts 476, 520 are operatively connected to the azimuth and elevation trackers' wheels 66, 68, respectively, the teeth 470, 518 of the gears 472, 516 being in meshing relation with teeth 468, 514, respectively, of the segment gears 466, 506 when the trackers are following the target, thereby causing, through the above-described mechanism, the azimuth and

elevation rate control levers 396, 398 to be operated by the trackers.

The shafts 476, 520 are rotatably mounted in bosses 522, 524 of bell-crank levers 526, 528 which are mounted upon a common fulcrum pin 530 supported by the fixed frame 408, the arrangement being such that when the commander is training the gun 40 on the target the gears 472, 516 are allowed to swing away from their associated segment gears 466, 506 when azimuth and elevation solenoids 534, 536 (Figs. 15 and 17) are energized by depressing the buttons 64 of the commander's grip 52. The solenoids 534, 536 and their operation will be hereinafter described together with a power failure solenoid 538. In order that the shafts 476, 520 shall be effectively journaled in the bosses 522, 524 of the bell-crank levers 526, 528, said shafts have pinned to them headers 537, 539 (Fig. 15) of universal joints forming part of driving connections described later.

In order to insure that the grip 52, when released, shall return to neutral position in which the lugs 436 (Fig. 16) of the lever 426 are spaced equal distances from the stop pin 438 and accordingly the segment gear 506 is centralized, there is secured to the shaft 497 a block 540 (Figs. 14 and 15) pivoted through a link 542 to a plunger 544 (Fig. 15) a lower portion of which is mounted in a housing 546 secured to the fixed frame 408. When the grip 52 is released, the plunger 544 assumes the position shown in Fig. 15 under the action of a spring 548 the upper end of which engages a washer 550 surrounding a reduced shank of the plunger and the lower end of which engages a washer 552 in engagement with a collar 554 pinned to the reduced shank of the plunger.

The dashpot 454 (Figs. 14, 15, 18, 19 and 20) for insuring against the azimuth and elevation levers 396, 398 of the control box 386 being moved too fast in either direction will now be described. The levers 482, 512 are secured to upstanding shafts 556, 558 journaled in recesses of covers 560 and upstanding supports 562 (Fig. 19) of the dashpot. Secured to the shafts 556, 558 are arms 563 (Figs. 18 and 19) which actuate a pair of double-acting plungers 564 (Figs. 18, 19 and 20) movable in cylindrical recesses 566 at opposite ends of the dashpot, a central chamber 568 and the four cylindrical recesses of the dashpot being filled with oil. The plungers 564 are identical, each of the plungers being provided with narrow passages 570 (Figs. 18 and 20) for restricting flow of oil from the cylindrical recesses 566 to large passages 572, 574 (Fig. 18) which are connected to the chamber 568. Practically unopposed return passage of oil from the chamber 568 to the recesses 566 is assured by the provision of passages 576 (Figs. 18 and 20) which are of considerable cross section and house check valves 578 which prevent flow of oil from the cylindrical recesses 566 to the chamber 568 but which, as above stated, allow free passage of oil from the chamber to the cylindrical recesses. It will be apparent that movement of the levers 482, 512, and accordingly the plungers 564, in either direction will be opposed by the oil in the cylindrical recesses 566, with the result that the speed at which the azimuth and elevation levers 396, 398 of the control box 386 can be operated is limited. When the commander rotates the grip 52 about the axes 418, 440 (Figs. 14 and 16) too rapidly, the springs 446, 452 of the overload couplings of the azimuth and elevation drives are compressed, the stops 422, 438 (Fig. 16) preventing the commander from moving the grip to such a position as to render

the overload couplings ineffective. So long as either of the springs 446, 452 of the overload couplings, respectively, is compressed, it continues to drive its associated lever 396 or 398 at a rate determined by the dashpot.

Trackers' driving and rate control mechanism

As above stated, the gun 40 is moved in azimuth, together with the turret 38, and in elevation relatively to the turret by the electric drive which is initially operated at a rate controlled by the commander through the mechanism just described. As above explained, after the commander has trained the gun 40 on the target he transfers control to the azimuth and elevation trackers who, by turning their tracking wheels 66 (Figs. 5, 21, 22 and 23), 68 (Fig. 5), mechanically rotate the turret 38, together with the gun, in azimuth and the gun in elevation, said wheels also being operatively connected through mechanism, part of which has been described and part of which will be described later, to the azimuth and elevation levers 396, 398 (Figs. 14 and 15). The speed of the azimuth and elevation motors 382, 384 varies in accordance with the amount of displacement of the tracking wheels 66, 68 in opposite directions from their starting positions, the power input being added algebraically through differentials to the mechanical movement thrown in by the trackers.

The azimuth and elevation trackers' hand wheels 66, 68, which are provided with cranks, are pinned to a shaft 580 (Figs. 21, 22 and 23) rotatably mounted in a head 582 (Figs. 21 and 22) of an upstanding column 584. In order to insure against the shaft 580 rotating when a sleeve 586 (Figs. 21 and 23) mounted upon the shaft is rotated by drive-back action of the electric drive mechanism, as will appear later, a clutch 588, 40 which will now be described, operatively connects the shaft 580 to the sleeve. Secured to the shaft 580 is a stud 590 fitting in a V-shaped notch 592 formed in a collar 594 which is loosely mounted upon the shaft 580 and has formed in it a plurality of circumferential spaced recesses 596 (Fig. 21) in each of which is arranged a spring 598. The outer ends of the springs 598 are in engagement with an abutment disk 600 (Figs. 21 and 23) which is also loosely mounted upon the shaft 580 and to which are secured two or more studs 602 (Fig. 21) each extending into a bore 604 of the collar 594. Secured in other portions of the bores 604 of the collar 594 are pins 606 extending in registering bores in a presser disk 608 in splined relation with the sleeve 586. Splined to the sleeve 586 and secured to the head 582 of the column 584 in interspersed relation are friction disks 610, 612, respectively, which, when the shaft 580 is idle, are forced into engagement with each other by the presser disk 608 acted upon by the spring-pressed collar 594, there being a space left between the collar and the abutment disk 600 when the shaft 580 is idle.

When the shaft 580 is rotated by the azimuth tracker, the stud 590 acting against the inclined face of the notch 592 forces the collar 594 to the right, as viewed in Fig. 21, into engagement with the abutment disk 600 against the action of the springs 598, thereby causing pressure of the friction disks 610, 612 against each other to be relieved and enabling the sleeve 586 to be driven through the presser disk 608. Should a feed-back force tend to rotate the sleeve 586 when the shaft 580 is idle, it will be apparent that the friction between the interspersed disks 610, 612 will pre-

vent rotation of the sleeve, and therefore the shaft.

Keyed to the sleeve 586 is a bevel gear 614 meshing with a bevel gear 616 which is secured to the upper end of a vertical stub shaft 618 rotatably mounted in bearings of the column 584 and which is formed integral with a gear 620 meshing with a gear 622 (Fig. 23) secured to the upper end of a vertical shaft 624 (Figs. 21, 22 and 23) rotatable in bearings supported by the column. Secured to the lower end of the vertical shaft 624 is a bevel gear 626 in driving relation with a bevel gear 628 (Figs. 22 and 23) secured to a horizontal shaft 630 extending through a bore 632 (Fig. 22) in a cage 634 of a differential 636 which is rotatable in bearings 638 mounted in a housing 640 and which, through mechanism hereinafter described, causes the rotation of the gear 100 (Figs. 21 and 22) which meshes with the ring gear 98.

Fixed to the vertical shaft 624 is a worm 642 (Figs. 21, 22 and 23) which drives a worm gear 644 keyed to a driving connection 646 journaled in a bracket 648 secured to and extending forward from the column 584. A bevel gear 650 (Figs. 21 and 23) fixed to the outer end of the driving connection 646 meshes with a bevel gear 652 pinned to the bottom of a vertical shaft 654 rotatably mounted in the bracket 648 and rotating through upwardly extending driving connections 656 the vertical shaft 476 (Figs. 14 and 15) which, as above explained, is rotatably supported in the boss 522 forming part of the bell-crank lever 526 mounted upon the fulcrum pin 530 secured to the fixed frame 408. Secured to the split collar 474 pinned to the upper end of the shaft 476 is the above-mentioned gear 472 which, when the turret 38 is in the control of the trackers, is in engagement with the segment gear 466 operatively connected, through mechanism above described, to the azimuth lever 396 of the control box 386. As above explained, the speed and direction of the azimuth motor 382 depends upon the degree and direction of displacement of the control box lever 396 from its neutral position.

A depending shaft 651 (Fig. 23) of the azimuth motor 382 is connected through an overload clutch 653 (Figs. 21, 22 and 23) to a shaft 658 to the lower end of which is secured a worm 660 in driving relation with a worm gear 662 secured to a horizontal shaft 664 (Figs. 21 and 23) rotatably mounted in bearings 666 (Fig. 21) of the housing 640. Fixed to the shaft 664 is a worm 668 which drives a worm gear 670 forming part of the differential cage 634.

Secured to the shaft 630, which, through mechanism above described, is manually operated by the azimuth tracker, is a bevel gear 672 (Fig. 23) meshing with bevel gears 674 (Figs. 22 and 23) rotatably mounted upon a shaft 676 carried by the differential cage 634. Also meshing with the bevel gears 674 is a bevel gear 678 secured to an output shaft 680 which is rotatably mounted in the cage 634 and is secured through a coupling 682 to a shaft 684 mounted for rotation in a bearing 686 (Fig. 22) in the housing 104 and having secured to it a worm 688 (Figs. 21 and 22) meshing with a large worm gear 690 secured to the upper end of the shaft 101. The shaft 101 has secured to its lower end the pinion 100 which, as above described, meshes with the fixed ring gear 98, rotation of the pinion causing the turret to move in azimuth about the vertical axis 108 (Fig. 5) of the ring gear.

It will be apparent from the foregoing that the rotation of the manually operated input shaft

630 (Figs. 22 and 23) causes rotation of the gear 612 of the differential and that displacement of the crankshaft 580, operating through the above-described mechanism, causes the azimuth rate control lever 396 of the control box 386 to be swung in order to set up a predetermined rate of speed to the worm gear 670 of the differential cage 634, with the result that these two movements are added algebraically through the differential and are transmitted through the output shaft 680 and the driving connections above described to the pinion 100 which meshes with the ring gear 98.

Portions of the mechanism for tracking the target in elevation are practically identical with the mechanism shown in Fig. 23 and need not be described in detail. Rotation of the wheels 68 of the elevation tracking unit causes rotation of a bevel gear 694 (Fig. 21), corresponding to the bevel gear 650 of the azimuth tracking unit, and meshing with a bevel gear 696 secured to the lower end of a vertical shaft 698 which is similar to and is positioned in substantially parallel relation to the azimuth shaft 654. The shaft 698 operates through driving connections 700 (Figs. 15 and 21) 20 the shaft 520 (Fig. 15) which, as above explained, is mounted for rotation in a bore of the boss 524 of the bell-crank lever 526. Secured to the upper end of the shaft 520 is the collar 519 between split portions of which the gear 516 is clamped. 30 As above stated, when the trackers are training the gun, the gear 516 is in driving relation with the segment gear 506 which is operatively connected to the elevation lever 398 of the control box 386.

35 Mechanism driven by an elevation differential (not shown) which is identical with the above-described azimuth differential and adds algebraically the manual input of the wheels 68 and the elevation electric motor 384 (Figs. 5 and 31) of the elevation rate control unit will now be described. 40 An elevation output shaft 702 (Fig. 7) of the elevation differential is coupled by a driving connection 704 to a shaft 706 which is mounted in bearings of a housing 708 secured to the trunnion block support 138 and which has secured to it a bevel gear 710 (Figs. 6 and 7) meshing with a bevel gear 712 secured to the lower end of a vertical shaft 714 rotatably mounted in bearings of a housing 716 secured to the outer portion of said trunnion block support. The vertical shaft 714 is operatively connected to a worm 718 which is rotatably supported in bearings of a housing 720 secured to the trunnion block support 138 and which meshes with a worm gear 722 secured to a horizontal shaft 724 rotatably secured in bearings 726 of the trunnion block support transverse web 142 and having secured to its central portion the gear 148 which meshes with the gun elevating segment gear 146.

Solenoids

As above explained, in order that the commander may render the grip 52, together with the above-described mechanism associated therewith, operative to actuate the azimuth and elevation levers 396, 398 of the control box 386, he must keep depressed the solenoid energizing buttons 64 (Figs. 14 and 16) of the grip. When the solenoids 534 (Figs. 15 and 17), 536 (Figs. 14, 15 and 17), which are of similar construction, are energized, their plungers 728 (Fig. 17) are moved away from opposed arms 730 (Figs. 15 and 17), 732 (Figs. 14, 15 and 17) of the associated bell-crank levers 526, 528, respectively, 70 against the action of associated springs 734 (Fig. 75)

17), with the result that the gears 472, 516 carried by the bell-crank levers are free to swing away from their opposed segment gears 466, 506. As above stated, the 30° pressure angle teeth of the segment gears 466, 506 and the gears 472, 516 are small, the construction and arrangement being such that when the gears 472, 516 are free to swing away from their associated segment gears upon the energizing of the solenoids 534, 536 there is no driving connection between the gears 472, 516 and their associated segment gears. When the commander releases the solenoid control buttons 64, the solenoids 534, 536 are de-energized, the solenoid plungers 728, actuated by the springs 734, operating against the arms 730, 732 of the bell-crank levers 526, 528 to swing the gears 472, 516 into operative engagement with the segment gears 466, 506.

In event of failure of power, it is desirable that the gears 472, 516 shall be moved and held away from their associated segment gears 466, 506. Accordingly, there is provided the above-mentioned master, or power failure, solenoid 538 (Figs. 14 and 15), comprising a plunger 738 and a spring 740. Operatively connected to the plunger 738 is a rearwardly extending arm 742 of a compound bell-crank lever 744 which is swiveled upon a fulcrum pin 746 suspended from the fixed frame 408, lateral arms 748 (Fig. 15), 750 of the bell-crank lever being arranged behind the heads of rods 752 (Fig. 15), 754 which are slidable in horizontal bores, respectively, of the fixed frame 408 and which extend through enlarged holes in the arms 730, 732 of the gear carrying bell-crank levers 526, 528, respectively. Secured to the forward end of each of the rods 752, 754 is a collar 756 (Fig. 14) and mounted upon each of the rods between a portion of the fixed frame and the head of the rod is a spring 758. When the current is on, the solenoid 538 is energized, the plunger 738 being moved to its position illustrated in Fig. 14, against the action of the spring 740, causing the springs 758 to be compressed and the collars 756 of the rods 752, 754 to be moved to inoperative positions away from the arms 730, 732 of the bell-crank levers 526, 528.

Should the power fail, the master solenoid spring 740, acting through the plunger 738, swings the compound bell-crank lever 744 counterclockwise, as viewed in Fig. 14, permitting the rods 752, 754 actuated by the spring 758 to move the bell-crank levers 526, 528 counterclockwise against the action of the springs 734 of the solenoids 534, 536, rearward movement of the rods being limited by the engagement of the plungers 728 (Fig. 17) of the solenoids 534, 536 with stop faces 760 of the solenoids.

When power is again supplied, the rods 752, 754 again move to their positions shown in Fig. 14, the springs 734 (Fig. 17) of the azimuth and elevation solenoids 534, 536 then being operative, through the bell-crank levers 526, 528, to move the gears 472, 516 into driving relation with the segment gears 466, 506, the trackers at such time being in control of the turret.

No drive-back through motor

When the turret 38 is being operated manually, the power having failed, it is desirable to insure against rotation of the input shafts 630 (Figs. 22 and 23) causing rotation of the azimuth and elevation differential cages 634, and therefore the rotation of the azimuth and elevation motors 382, 384. Accordingly, there is splined

to the outer end of each of the shafts 664, which are driven by the azimuth and elevation motors 382, 384, a collar 762 (Figs. 21, 22 and 23) which has circumferentially arranged teeth 764 and a circular groove 766 in which fit rolls 768 carried by bifurcated arms of an L-shaped lever 770 mounted upon a fulcrum pin 772 supported by a bracket 774 secured to the housing 640. Pivoted to the lever 770 is a rod 776 operatively connected through an overload coupling 778 to a rod 780. The upper end of the rod 780 is pivoted to an arm 782 which is swiveled upon a fulcrum pin 784 secured to the column 584 and carries a spring-pressed plunger 786. Surrounding the shaft 664 and secured to one end of the housing 640 is a toothed plate 788 (Figs. 21 and 23) arranged opposite the teeth 764 of the collar 762. When the spring-pressed plunger 786 on the lever 782 registers in the upper of two openings 790 in an arcuate lug 792 secured to the column 584, the collar 762 is so positioned that its teeth 764 are spaced from the toothed plate 788. When the power fails, the lever 782 is swung to a position in which the plunger 786 registers in the lower opening 790 of the lug 792, causing the teeth 764 of the collar 762 to be forced against the toothed plate 788, thereby insuring against movement of the shaft 664 when the input shaft 630 is rotated.

Gun elevation limit stops

As above stated, the gun 40 is moved about the axis 144 (Fig. 7) of its trunnions 132 in the arcuate opening 122 (Fig. 1) of the turret 38 through a range varying from minus 15° to 90° from the horizontal. When the rate control mechanism is operative, it is desirable automatically to stop the gun when its tube 330 has reached its limits of movement in elevation. Accordingly, there are secured to the arcuate shield 154 deflecting cams 794, 796 (Fig. 5) which are constructed and arranged to swing a lever 798 just before the gun has reached the upper and lower limits, respectively, of its movement in elevation. The lever 798 is secured to a rod 800 which is fulcrumed in the fixed frame 408 and has secured to it a forked lever 801. Meshing with a tooth of a lever 802 which is fulcrumed on a rod 803 carried by the fixed frame 408 and the lower end of which carries a switch controlling rod 804 normally held in a neutral position, shown in Fig. 5, by a spring (not shown). When the deflecting cams 794, 796, by reason of their acting upon the lever 798 and other mechanism above described, cause the switch controlling rod 804 to be moved to the left or right, respectively, upward or downward movement of the tube of the gun is stopped. Since switches for limiting movement of electrically powered objects in opposite directions are well known and form no part of the present invention, a detailed description of such switch is believed to be unnecessary.

When the power has been turned off, or has failed, and the gun is being trained entirely through the trackers' manual control mechanism above described, the limits of movement of the gun in elevation are determined by the engagement of stops 806 (Figs. 5, 6 and 7), which are secured to the segment gear 146, with shoulders 808 (Figs. 6 and 7) of the transverse web 142 of the trunnion block supports 138, 140.

Sight drives from gun elevating mechanism

In order automatically to vary the elevation of the three elbow telescopes 58, 60, 62 and the open

sight 48 in accordance with changes in the elevation of the gun 40, the gun elevating shaft 724 (Figs. 7 and 30) has secured to its right end a bevel gear 810 which is enclosed in a housing 812 secured to the trunnion block support 140 and meshes with a bevel gear 814 secured to the upper end of a vertical driving connection 816. The lower end of the driving connection 818 has secured to it a bevel gear 818 which is rotatably mounted in a housing 820 secured to the trunnion block support 140 and drives a bevel gear 822 secured to a horizontal shaft 824 mounted for rotation in said housing. The shaft 824 is operatively connected through a drive 825 (Figs. 5, 8 and 30) extending along the floor and the right side wall of the turret to a bevel gear 826 secured to the lower end of an input shaft 828 (Figs. 5, 8, 27 and 30) extending upward into the lead setting box 74. As will be explained later, changes in the elevation of the gun 40 and in the elevation deflection angle between the elbow telescopes 58, 60, 62 and the gun are added algebraically in a differential 830 (Fig. 27) which is operatively connected to the shaft 828 and which, through mechanism hereinafter described, drives an elevation output shaft 832 of the lead setting box 74. The connections between the elevation output shaft 832 of the lead setting box 74 and the elbow telescopes 58, 60, 62 will be described later.

The drive 825 (Figs. 5, 8 and 30), through which the horizontal shaft 824 (Figs. 7 and 30) is connected to the elevation input shaft 828, is operatively connected through driving connections 834 (Figs. 5, 8, and 30) to a bevel gear 836 secured to the lower end of a shaft 838 (Figs. 5, 8, 13 and 30) coupled to the shaft 842 which, through mechanism above described and best shown in Fig. 13, gives the open sight 48 in elevation.

Sights

As above stated, the elbow telescopes 58, 60, 62 may be angularly adjusted in azimuth and in elevation with relation to the gun to vary the azimuth and elevation deflection angles between the gun and the sights, through mechanism which will be described presently and is operated by the commander as he observes the effect of fire upon the target. The sight mechanism through which the elbow telescopes 58, 60, 62 are angularly adjusted in elevation and in azimuth with relation to the gun is identical.

Each of the sights 130 (Figs. 1, 2, 5, 24, 25, 27 and 30) comprises an elbow telescope 58, 60 or 62 having a pair of ribs 840 (Figs. 24, 25 and 26) and mounted upon the ribs is an adapter sleeve 842 (Fig. 25) which is rotatable in a cylindrical bore 844 of a block 846 (Figs. 24, 25 and 27) comprising two parts secured together by screws 847. The adapter sleeve 842 has a portion 848 (Fig. 26) of reduced diameter provided with a pair of slots 850 in which fit extensions 851 (Figs. 25 and 26) of one of the ribs 840 of the telescope. The block 846 has formed integral with it an upper trunnion 852 and secured to it by screws 854 is a lower trunnion 856 (Figs. 24, 25 and 27), said trunnions being swiveled for rotation about a common axis 858 in bores 860, 862 of a housing 864. The housing 864 of the sight 130 is rotatably mounted upon a hanger pin 866 (Figs. 24 and 25) supported by a bracket 868 secured by screws 870 to the wall of the turret 38. The sides 872 and a gear box 874 of the housing 864 are formed integral and are secured by screws 876 (Fig. 24) to the top of the housing, the housing being secured in its

vertical position upon the hanger pin 866 by nuts 878 (Fig. 25) threaded onto a screw 880 which passes through an enlarged recess 882 of the housing and is secured to the turret wall. In order to insure that the axis 858 of the trunnions 852, 856 shall be exactly vertical, a spirit level 884 (Fig. 24) is secured to the housing 864. The inner vertical faces 886 (Fig. 24A) of the housing 864 are cylindrical and are centered about the axis 858 of the trunnions 852, 856, the curved lateral sides 888 of the block 846 being complementary to and just clearing the faces 886 of the housing.

Mounted in a recess 880 (Fig. 25) of the block 846 is a bevel gear 892 which is secured to a flange of the adapter sleeve 842 by screws 894 (Fig. 26), a two-part plate 896 being forced by screws 898 against the inside faces of the block and the inner rib 840 of the elbow telescope 58, thereby insuring against movement of said telescope lengthwise of its axis 890 with relation to the block 846. Secured by screws 902 (Fig. 25) to the adapter sleeve 842 is a hood 904 which affords protection for the portion of the telescope 58 extending outside of the turret. Since the elbow telescopes 58, 60 and 62 are of the standard type now in use and do not form part of the present invention, it will not be necessary to describe said telescopes in detail.

In order to swing the block 846 into different angularly adjusted positions about the axis 858 of its trunnions 852, 856 to vary the azimuth deflection angle between the gun 40 and the elbow telescope 60, the trunnion 856 has keyed to it a gear 906 (Figs. 24, 25 and 27) which meshes with a worm 908 pinned to a shaft 910 which, as will appear later, is operatively connected to an azimuth output shaft 912 (Figs. 5, 27, 28 and 29) of the lead setting box 74, which, as above explained, is controlled by the commander.

To rotate the elbow telescope 60 in the block 846 about its horizontal axis 900 (Figs. 24 and 25) the bevel gear 892, which is secured to the adapter sleeve 842, meshes with a bevel gear 914 which is arranged in a recess of the block and is fixed to the upper end of a shaft 918 fitting in a concentric vertical bore of the trunnion 856. Secured to the lower end of the shaft 918 is a gear 920 meshing with a worm 922 rotated by and also movable lengthwise along a shaft 924 rotatably mounted in the gear box 874 of the housing 864.

It will be apparent that rotation of the elbow telescope 58 about the axis 858 of the trunnions 852, 856 will, unless compensated for, cause the bevel gear 892 to turn about the horizontal axis 900 and introduce an elevation error into the sight. In order to insure against this occurring, the worm 922 during movement of the block 846 about the axis 858 of the trunnions 852, 856 is moved relatively to the shaft 824 by a yoke 926 secured by screws 928 to a rack 930 which is slideable lengthwise in bores 932 (Fig. 27) of the gear housing 874 and meshes with a gear 934 (Figs. 24 and 25) secured to the trunnion 856 and having the same pitch diameter as the gear 920. With such a construction it will be apparent that when the block 846 is swung about the vertical axis 858 of the trunnions to vary the azimuth lead the worm 922 slides along its shaft 924 the proper amount to insure against the gear 892 being rotated with relation to the block about its axis 900.

As above explained, the proper lead corrections are made in the lead setting box 74, which is operated by the commander in accordance with

his observation of tracer bullets fired upon the target.

Lead setting box

Since the gun 40 moves in azimuth, together with the turret 38, it is only necessary to swing the elbow telescopes 58, 60, 62 about the axis 858 (Figs. 24 and 25) of their trunnions 852, 856 in order to give the gun the proper lead in azimuth. It will be apparent, however, that since the gun is moved in elevation with relation to the turret it is necessary to have each of the elbow telescopes swing about its horizontal axis 900 to the same degree that the gun swings about the axis 144 (Fig. 7) of its trunnions 132 and to add to such movement the desired lead in elevation. As above stated, the elevation deflection angle may be varied by the commander by rotating the hand wheel 72 which is fixed to the outer end of a shaft 936 (Figs. 27 and 28) journaled in a bearing of the lead setting box 74. Pinned to the inner end of the shaft 936 is a bevel gear 938 meshing with a bevel gear 940 secured to an upstanding shaft 942 to which is pinned a worm 944 meshing with a gear 946 keyed to an index shaft 948. Pinned to the rear end of the shaft 948 is a large gear 950 in driving relation with a smaller gear 952 (Fig. 27) secured to a lower horizontal shaft 954 rotatably mounted in the lead setting box. Rotation of the shaft 954 is transmitted through bevel gears 956 to an input shaft 958 of the above-mentioned differential 830. As above stated, changes in elevation of the gun are introduced into the differential 830 by the elevation input shaft 828 (Figs. 5, 8, 27 and 30) which is movable in response to movement of the segment gear 146 (Figs. 5, 6, 7 and 30) of the gun 40. The elevation components from the lead setting box and the gun elevation input shafts 958, 828 are added algebraically in the differential 830, which comprises a cage 960 to which is secured a gear 962 (Figs. 27 and 28) meshing with a gear 964 fixed to the elevation output shaft 832 (Figs. 5, 27, 28 and 29) which is operatively connected through driving connections 966 (Figs. 5 and 30) to the elevation shafts 924 of the commander's and trackers' sights.

In order to register the elevation deflection angles, there are provided index and vernier dials 968, 970 (Figs. 28 and 29) which are calibrated in mils and are viewed through a window 971 (Fig. 29) in the top of the lead setting box 74. The dials 968, 970, respectively, are freely mounted upon and pinned to the shaft 948, the index dial 968 being rotated at one-ninth the speed of the vernier dial 970 by means of a gear train comprising a gear 972 (Figs. 27 and 28) pinned to the shaft 948, a pair of idler gears 974 mounted upon a fulcrum pin 976 fixed to the lead setting box 74, and a gear 978 freely rotatable upon the shaft 948 and pinned to the index dial 968. In the illustrative construction the maximum lead of the gun in elevation is approximately 450 mils, or about 25°, the index dial at such time having been rotated slightly less than one-half of a revolution to the right or to the left from its neutral position, shown in Fig. 29, in which position the zero marks on the dials register with marks 980 on the lead setting box 74.

The azimuth lead of the gun is varied by the rotation of the hand wheel 70 which is pinned to the outer end of a shaft 982 (Figs. 27 and 28) journaled in the lead setting box 74. Secured to the inner end of the shaft 982 is a bevel gear 984 meshing with a bevel gear 986 pinned to a vertical shaft 988 which carries a worm 990 in

driving relation with a gear 992 secured to an index shaft 994. Pinned for rotation with the shaft 994 is a vernier dial 996. The inner end of the shaft 994 has secured to it a gear 998 (Fig. 28) driving a compound gear 1000 operatively connected to a gear 1002 which is fixed to the azimuth lead output shaft 912 (Figs. 5, 27, 29 and 30). The shaft 912 through upwardly extending driving connections 1004 (Figs. 5, 27 and 30) operates the shaft 910 (Figs. 24, 25 and 27) of the commander's sight 130 and through driving connections 1006 (Figs. 5 and 30) extending downward and along the right wall of the turret operates the shafts 910 of the trackers' sights 130.

Freely mounted upon the shaft 994 (Figs. 27 and 28) is an index dial 1008 (Figs. 28 and 29), and secured to the shaft is a pinion 1010 which meshes with a compound gear 1012 which is rotatably mounted upon a fulcrum pin 1014 secured to the lead setting box 74 and which meshes with a gear 1016 rotatably mounted upon the shaft 994 and pinned to the index dial 1008, the arrangement being such that the index dial partakes of one-ninth of the rotation of the shaft 994 and accordingly the vernier dial 996. In the lead setting box 74 is a window 1018 (Fig. 29) through which the commander may observe the amount of lead in azimuth. The calibration of the azimuth vernier and index dials 996, 1008 is similar to that of the elevation vernier and index dials 970, 968. As in the elevation lead setting mechanism, the maximum lead in azimuth is 450 mils, or approximately 25°.

The course of a target may be divided into two components, one tangential and the other radial to the line of sight. In tracking the target the tangential component is considered in computing the azimuth lead and the radial component is considered in computing the elevation lead.

When the tangential component is clockwise, as viewed from above (Fig. 32), the azimuth lead, that is, the lead of the gun in relation to the line of sight as viewed from above, is also clockwise. It will be apparent that the tangential component remains in the same direction so long as the target remains on the same general course, such, for example, as from A to B. Should the target reverse its course, the azimuth lead would be counterclockwise.

It will be noted, however, that the radial component changes from an inward or incoming direction, shown at A, Fig. 32, to an outward or outgoing direction, as shown at B, during travel of the target in its course from A to B. Accordingly, while following the target through course A to B, the elevation lead will have to be changed from an inward to an outward one. The inward elevation lead may be said to require an upward vertical deflection of the gun from its line of sight and the outward lead may be said to require a downward vertical deflection of the gun from the line of sight. It is evident that the elevation lead will be maximum at the extreme ranges A or B and will be reduced to zero at the minimum range C, the elevation lead changing in direction at this point. The course A to B may be referred to as a clockwise course, the portion of the course to the left of the minimum range point C being considered the incoming part of the course and that portion of the course to the right, the outgoing part of the course. It will be understood that for a clockwise direction course the gun will have an upward vertical deflection for the incoming part of the course and a downward vertical de-

fection for the outgoing part of the course. This will also hold true for a course where no tangential component is present.

When there is no lead in azimuth, the zeros on the index and vernier dials 1008, 996 of the azimuth lead setting mechanism are in alignment with marks 1019 on the lead setting box 74, and when there is no lead in elevation the zeros on the vernier and index dials 968, 970 of the elevation lead setting mechanism are in alignment with the marks 986 of the lead setting box. When the commander rotates the azimuth wheel 70 clockwise, as viewed from the front of the lead setting box 74, there is provided a clockwise lead in azimuth, the azimuth index and vernier dials 1008, 996 moving in the direction of the arrow 1021, the dial numbers which increase progressively to the left from zero and are colored blue then being read. When the commander rotates the azimuth wheel 70 in a counterclockwise direction from its neutral position, a counterclockwise lead in azimuth is provided, the dials 1008, 996 moving in a direction opposite to the direction of the arrow 1021 and dial numbers which increase progressively from the right of zero and are colored white being read.

When the elevation wheel 72 is rotated clockwise, as viewed from the front of the lead setting box 74, from a neutral position in which there is no lead in elevation and in which the zeros on the index and vernier dials 968, 970 are in registration with the marks 986 on the lead setting box 74, the gun will be given an outgoing lead in elevation, the dials moving in the direction of the arrow 1023 and the commander reading blue dial numbers which increase progressively to the left from zero, as viewed in Fig. 29. When the elevation wheel 72 is turned counterclockwise, the gun will be given an incoming lead, the dials 968, 970 moving in a direction opposite to the direction of the arrow 1023 and white dial numbers which increase progressively to the right from zero being read.

In order to insure against breakage of the lead setting mechanism above described due to applying too much force to the wheels 70, 72, there are provided stops 1020 (Figs. 27 and 28) which, when the index dials 968, 1008 operatively connected to the elevation and azimuth lead setting mechanism have been rotated just less than one-half of a revolution and accordingly register approximately 450 mils, are engaged by abutments 1022, best shown in Fig. 27, formed upon collars 1024 secured to the shafts 936, 982. The mechanism for operating said stops 1020 comprises cams 1026 (Fig. 27) carried by the index dials 968, 1008, respectively. Secured to the inner ends of shafts 1026 which are journaled in the lead setting box 74 and to which the stops 1020 are pinned are levers 1030. Just before the index dials 968, 1008 have reached the limits of their movement, the levers 1030 are engaged by the cams 1026, causing the stops 1020 to be raised into positions to be engaged by the abutments 1022 on the collars 1024, thus preventing the shafts 936, 982 from being turned any farther by the commander. During the normal operation of the lead setting device, the stops 1020 are held in their depressed positions, shown in Fig. 27, against screws 1031 out of the path of movement of the abutments 1022 by springs 1032 which operate against the levers 1030.

In order that the commander while viewing the target may have a fair idea of the magnitude of the leads in azimuth and elevation, there are pro-

vided clicker devices comprising recessed disks 1034 (Figs. 27 and 28) which are secured to the forward ends of the index shafts 948, 994 and are engaged by leaf springs 1036 secured by screws 1038 to the lead setting box 74. For every 25 mils of rotation of each of the index shafts 948, 994 one of the springs 1036 falls into a depression 1040 of the associated disk 1034, causing an audible click.

- 10 In the use of the above turret the commander, standing upon the platform 48 (Figs. 5, 8 and 9), spots the target through the open sight 48 and initially trains the gun on said target by the use of the grip 52 which operates the above-described rate control mechanism. The commander then moves to a seated position upon the stool 58 (Figs. 5 and 8) and continues to train the gun on the target by the use of the grip 52 while observing said target through the elbow telescope 58.
- 15 20 The commander then releases the solenoid control buttons 84 on the grip, thus transferring control of the turret to the azimuth and elevation trackers who operate the wheels 86, 88 respectively, as above described, to retain the fire 25 of the gun on the target. After releasing the control of the gun to the trackers, the commander observes the effect of the fire on said target and by turning the azimuth and elevation wheels 70, 72 of the lead setting box 74 throws the necessary 30 leads into the trackers' sights to concentrate fire on the target.

The gun sight disclosed herein is described and claimed in a divisional application Serial No. 684,864, filed July 19, 1946 in our names.

- 35 Having described our invention, what we claim as new and desire to secure by Letters Patent of the United States is:

1. In an armed turret, a gun, sighting means therefor, means for swinging the gun together with the turret in azimuth and for swinging the gun in elevation with relation to the turret to train the gun on a target observed through said sighting means, said sighting means being mounted for rotation with relation to the gun about two axes disposed at right angles to each other to vary the azimuth and elevation leads of the gun with relation to the sighting means, a sight through which an observer may view the effect of fire of the gun upon the target, and means controlled by the observer for varying said azimuth and elevation leads.

2. The combination with a turret rotatable about a vertical axis of a gun movable in azimuth together with the turret and in elevation relatively to the turret, tracking means for rotating the turret together with the gun about said vertical axis and for moving the gun in elevation about a horizontal axis, sights each carried by the turret and mounted for rotation about a vertical axis with relation to the turret, each of said sights also being movable in elevation about a horizontal axis to the same degree as and also relatively to the gun, and means independent of said tracking means for moving the sights in azimuth and in elevation with relation to the gun in order to vary the azimuth and elevation deflection angles between the sights and the gun in accordance with the observed fire of the gun upon the target.

3. The combination with a rotatable turret of a gun movable in azimuth together with the turret and in elevation relatively to the turret, manually operated means for rotating the turret, manually operated means for moving the gun

75 ret, manually operated means for moving the gun

in elevation, power-operated rate control units operatively connected to said manually operated turret rotating and gun elevating means respectively to aid in tracking a target, a pair of sights mounted in the turret for enabling azimuth and elevation trackers in control of said manually operated means respectively to follow the target, and means for varying the azimuth and elevation deflection angles between each of the sights and the gun in accordance with the observed effect of fire on the target.

4. In combination with a rotatable turret, a gun movable in azimuth together with the turret and in elevation with relation to the turret, manually operated means for rotating the turret, manually operated means for moving the gun in elevation, power units for moving the gun and the turret in azimuth and the gun in elevation respectively, azimuth and elevation levers for controlling the rate of speed of said power units, connections between the manually operated means and said levers respectively for displacing said levers in accordance with the displacement of said manually operated means, a pair of sights mounted in the turret for enabling azimuth and elevation trackers in control of said manually operated means respectively to follow a target, and means for varying the azimuth and elevation deflection angles between each of the sights and the gun in accordance with the observed effect of fire on the target.

5. In an armed turret, a gun, a pair of members, power-driven rate control means for moving the turret together with the gun in azimuth at predetermined rates in accordance with the displacement of one of the members and for moving the gun in elevation at predetermined rates in accordance with the displacement of the other member, a manually operated grip, yieldable connections between the grip and the members, mechanism for limiting displacement of the grip to limit the displacement of said members, and dashpots operatively connected to said connections to insure that the members shall not move above a predetermined speed, thus insuring against too rapid acceleration and overcontrolling of the turret and the gun in azimuth and the gun in elevation.

6. In combination with a turret, a gun, power-operated means for moving the turret together with the gun in azimuth and for moving the gun in elevation with relation to the turret, levers movement of which controls said power-operated means to regulate the speed of the turret and the gun in azimuth and the gun in elevation, a grip movable about two axes disposed approximately at right angles to each other, connections responsive to movement of the grip about one axis for displacing one of the levers to cause the turret and the gun to be moved in azimuth at a selected rate, connections responsive to movement of the grip about said other axis for displacing the other lever to cause the gun to be moved in elevation at a selected rate relatively to the turret, a dashpot operatively connected to each of said connections to prevent said levers from being moved too rapidly, said connections

between the grip and the place where the dashpot is connected thereto being yieldable so that the grip may be moved yieldingly against the resistance of the dashpot, and centralizing means for causing the dashpot and said connections, including the grip, to assume neutral positions when the grip is released.

7. The combination with a rotatable turret of a gun, combined manual and power-operated mechanism for moving the gun together with the turret in azimuth, combined manual and power-operated mechanism for moving the gun in elevation with relation to the turret, said mechanisms comprising members operated by azimuth and elevation trackers respectively, azimuth and elevation rate regulating levers which are movable in response to movement of said members to vary the speed of said power-operated mechanisms in accordance with the displacement of said members, azimuth and elevation differentials in which the manual and power-operated movements of said mechanisms respectively are added algebraically, and means for rendering portions of the power-operated mechanisms and the differentials respectively inoperative when power is off to insure against any manually operated drive-back to motors of said power-operated mechanisms.

8. In an armed turret, a gun, power-driven means for moving the turret together with the gun in azimuth and the gun in elevation with relation to the turret, azimuth and elevation control members movable respectively to vary the rate of movement of the turret and the gun in azimuth and the gun in elevation with relation to the turret, mechanism comprising a grip actuated by a spotter for operating the azimuth and elevation control members respectively, connections actuated by azimuth and elevation trackers respectively for operating the azimuth and elevation control members, and means associated with said grip for rendering said connections operative or inoperative at the will of the spotter.
